UNITED STATES PATENT OFFICE.

EDGAR M. CLARK, OF NEW YORK, N. Y., ASSIGNOR TO STANDARD OIL COMPANY, OF NEW YORK, N. Y., A CORPORATION OF NEW JERSEY.

PROCESS OF DISTILLING CRUDE PETROLEUM AND PRODUCT THEREOF.

1,413,260.

Specification of Letters Patent. Patented Apr. 18, 1922.

No Drawing.

Application filed March 31, 1919. Serial No. 286,262.

To all whom it may concern:

Be it known that I, EDGAR M. CLARK, a citizen of the United States, residing at New York, in the county of New York and State 5 of New York, have invented a new and useful Improvement in Processes of Distilling Crude Petroleum and Product Thereof, of which the following is a specification.

The present invention is directed to certain improvements in the art of distilling crude petroleum oil and will be fully understood from the following specification: In order to obtain from crude petroleum oil a maximum yield of valuable products, it is in general required that the oil be distilled to the point of dryness, that is, until the residue of distillation is petroleum coke. Offsetting the higher yield of valuable products obtained in this fashion however, there are attendant disadvantages well-known to those skilled in the art, which disadvantages become more and more serious as the specific gravity of the crude oil increases. Thus, in a case of the ordinary quality of Mexican crude petroleum now produced and having a Baumé gravity of from 21 to 23°, there is obtained a coke residue very high in sulphur and amounting to as much as 14 to 18% of the weight of the crude distilled with an accompanying gas loss of 2 to 5%. Under many conditions, this coke residue may be worth less than the cost of removing it from the stills. A typical process of running Mexican crude petroleum to coke may be represented substantially as follows:

Yields.

Naphtha	14%
Refined oil	10%
Gas oil or high-grade fuel oil	56%
Coke and gas	20%

It will be understood, of course, that the 56% gas oil or high-grade fuel oil fraction will usually be subjected to further refining operations for the recovery of paraffin wax and the separation of high-viscosity fractions suitable for lubricants, the extent to which such further refining is carried being dependent upon the quality of the oil, the equipment of the refinery and the demand for the highly refined products. Under the most favorable conditions, however, the loss in coke and gas together with the expense of maintaining the refinery equipment and re-

moving the coke from the stills renders this method of running so unattractive that many of the larger refiners prefer to merely "skim" the ordinary grade of Mexican crude petroleum, that is, distill off only about 15% which is less than the total content of 60 naphtha and refined oil, marketing the whole of the 85% residue as a low-grade fuel oil, which must compete with coal as a bunker fuel for ships. Aside from the waste of the valuable lubricant fractions and wax of the 65 crude oil inherent in the use of this skimming process, there is a further disadvantageous result of considerable economic importance. This is the failure to produce a supply of a heavy petroleum oil satisfactory for use in 70 the more highly developed cracking processes for the production of gasoline or naphtha. Thus, according to the method described in the United States patent to William M. Burton, No. 1,049,667, it is possible to produce 75 at a profit, from any ordinary grade of gas oil or fuel oil, a considerable quantity of gasoline, and this process which has come into wide use throughout the United States has measurably added to the gasoline supply. The reduced Mexican crude, however, that is the low grade fuel oil produced by skimming Mexican crude oil, does not constitute a satisfactory raw material for treatment according to the Burton cracking 80 process referred to, or according to any other cracking process which has yet come into wide use. One reason for this unsatisfactory operation of the cracking process referred to, is that the accumulation of carbon in the 85 cracking stills is so rapid that the amount of gasoline which can be produced before cleaning is required is cut to a very small figure.

By the present invention there is provided 90 a method of obtaining from crude oil, and particularly from heavy asphaltic-base crudes, such as the Mexican, a maximum yield of valuable products including heavy hydrocarbons suitable for use as a 100 charging stock in cracking stills, without encountering any of the difficulties met with in the heretofore known process of running such crude down to coke. In brief, it may be said that my present process contemplates 105 arresting the distillation at the point where the crude oil is reduced to a high-melting-point pitch, and then fluxing this pitch with

a quantity of fuel oil sufficient to produce a product fluid at ordinary temperatures and capable of being marketed as a liquid fuel product. The preferred process in accordance with my present invention, and as applied to Mexican crude petroleum, may be described as follows:

The apparatus for conducting the process consists of a string of continuous stills, for example, twelve stills arranged to constitute a continuous battery with provisions for feeding the first still of the string and causing the oil to overflow from each still into the next succeeding still, each still having vapor pipes and condenser equipment, all according to common practice. Each still will, furthermore, be provided with the usual means for introducing open steam (i. e., directly injecting steam), so that the distillation may be conducted with fire and steam. The last still of the string will, furthermore, be equipped with means for introducing the fluxing oil into the end at which the pitch residue enters, the draw-off being at the opposite end as in ordinary practice.

In addition to the ordinary continuous still equipment described in the foregoing, it is desirable that the plant in which my process is carried out be likewise equipped with an adequate number of pressure cracking stills, such as are described in the patent to Burton referred to.

In the handling of the oil according to the method of the present invention, and with the equipment described, the crude oil is continuously pumped into the first still of the series, is there subjected to the heating effect of the still furnace, supplemented by the continuous injection of steam (preferably superheated steam) into the oil body, distills off its lighter components, overflows to the next still in the series, and is thus subjected to distillation at increasing temperatures successively in its course through the battery of stills. The distillation will be conducted at such a rate that approximately 75% of the total volume of the crude will have been distilled off before the residue reaches the last still of the string. It will, in general, be unnecessary to fire this last still. The 25% residue of the Mexican crude petroleum will be a pitch of very high melting point, for example, 192° F., but is a relatively mobile fluid at the temperature at which it enters the fluxing still. The process of distillation being a continuous one, as described, there will be a continuous stream of this high-melting-point pitch flowing into the inlet end of the fluxing still, and simultaneously there will be pumped into the same end of the still, preferably in a heated condition, an approximately equal volume of the tar or residue resulting from the practice of the cracking process in the pres-

sure stills referred to. This "pressure tar" may, for example, have the following specification:

Gravity	23.5° B.
Viscosity	49 at 100° F. (Saybolt).
Pour	Below zero.
Flash	195° F.

70

The two streams, i. e. that of pressure tar and high-melting-point pitch enter the still continuously and simultaneously at one end, both being preferably at an elevated temperature as described, and traverse the length of the still, being meanwhile subjected to continuous agitation by the superheated steam from the apertures in the submerged steam coils in the still. Under these conditions, the fluxing process proceeds satisfactorily and there is formed an intimate mixture of the two fluids with the incidental result that lighter constituents of the pressure tar, should any be present, are distilled off and pass to the condensers with the steam. The fluxed product flows out of the end of the still opposite that at which its constituents entered, and is pumped off to storage, preferably through heat exchangers, in the ordinary manner. This fluxed fuel produced as above described may have the following approximate specifications:

Gravity	14.3° B.
Viscosity	870 at 212° F. (Saybolt).
Pour	65° F.
Flash	290° F.

95

100

As will appear from the foregoing specifications, it constitutes a petroleum product sufficiently mobile to be marketable as a liquid fuel, that is, it is capable of being handled as a fluid under ordinary atmospheric conditions, requiring the use of only a small amount of steam for heating purposes to keep it fluid under adverse conditions. It does not have the tendency to increase in viscosity and cold test figure during storage to the extent that the skimmed Mexican crude exhibits these undesirable properties.

The continuous distillation of the Mexican crude petroleum in the manner above described therefore gives approximately the following yields of distilled products:

Naphtha	14%
Refined oil	10%
Gas and fuel oil (including high viscosity oils and wax)	50%
Liquid fuel constituent	25%
Gas	1%

120

125

According to the equipment of the refinery, the quality of the oil and demand for the refined products, the 50% gas or fuel oil cut from the crude, or any part thereof, may be re-run for the separation of high-viscosity lubricants and other highly refined heavy

130

oils, or pressed for the recovery of wax, or both. In any event, the whole of this 50% fraction of the Mexican crude oil is marketable as a gas oil or fuel oil of good quality, 5 constituting as it does a distillate and not a reduced crude product.

I prefer to employ either the whole of this intermediate fraction of the Mexican crude or that portion remaining after the wax and 10 lubricants are extracted, as a charging stock for the production of gasoline by a pressure distillation process, such as that of Burton referred to. In such a pressure distillation process I may, for example, charge into the 15 pressure still 12,000 gallons of the intermediate fraction of the Mexican crude, and as a result of the cracking operation conducted in the still, produce therefrom from 6,000 to 7,200 gallons; that is, from 50 to 60% of 20 crude gasoline, leaving in the still at the end of the cracking operation a residue of from 40 to 50% which residue constitutes the pressure tar referred to above as being the preferred product employed for fluxing the 25 pitch residue. While this pressure tar is in itself a suitable material for re-running in the pressure stills for the production of a further quantity of gasoline, it requires redistillation to put it in good condition for such 30 re-running in the pressure stills, and, furthermore, the chemical changes which it has undergone in the still render it less desirable as a charging stock for the pressure stills than is a fresh distillate from crude oil. On 35 the other hand, while the pressure tar is not so desirable as a fresh charging stock for the pressure stills, it is a particularly advantageous fluxing agent by reason of its relatively low cold test and viscosity.

40 The general scheme of operation of the preferred distilling process, according to the present invention, is therefore as follows:

100 barrels of Mexican crude is distilled with fire and steam in a continuous distillation apparatus as described, to produce 75% of distillate and 25% of high-melting-point 45 pitch residue. A large proportion of the heavier distillate, for example, 50 barrels is used as a charging stock for pressure stills, 50 being subjected to the cracking treatment for the production of gasoline and yielding approximately 50%, or 25 barrels of gasoline, with a residue of 25 barrels of pressure tar. This pressure tar is used for fluxing off the 55 25 barrels of high-melting-point pitch residue to give 50 barrels of low-grade liquid fuel. In the example given therefore the approximate gross yield from 100 barrels of Mexican crude would be 40 barrels naphtha 60 and refined oil, 10 barrels paraffin wax and lubricants and 50 barrels bunker fuel, distillation losses being neglected since they are very small with the present method of operation. It will be seen, therefore, that by my 65 invention it is possible to obtain a maximum

yield of the most valuable products; that is, naphtha and refined oil, wax and lubricants, without carrying the distillation down to coke, either in the original distillation of the crude oil or in the re-distillation of pressure 70 tar. All of the disadvantages which follow from carrying the distillation to coke are thus avoided, all of the advantages of continuous distillation with steam are obtained, the pressure still equipment of the refinery is 75 assured of an adequate supply of high-grade charging stock suitable for conversion into gasoline, and an advantageous means of disposing of the pressure tar without further treatment thereof is offered. 80

In the treatment of higher grade crude oils, such as mid-continent crude oil which do not ordinarily yield more than 2-3% coke by distillation to dryness, I recommend the following procedure. Using the same equipment as above described, the mid-continent crude oil is reduced to a bottom of approximately 15% in the first eight stills of the series. The last four stills are used in succession in the following manner: 90

The stream of 15% bottom is run into one of these stills (previously empty) up to the capacity of the still, when it is shut off or diverted to another empty still. The full still is now fired, and steam blown in in 95 the usual manner until there has been produced, for example, 10% of slop distillate high in crystalline wax and lubricants and, perhaps, 1% of still wax distillate if the latter is desired. There will 100 then remain in the still a high-melting-point pitch, representing about 4%, for example, of the crude oil. This pitch will now be fluxed with an approximately equal quantity of a residual or by-product petroleum 105 hydrocarbon of the grade of a fuel oil, such, for example, as the pressure-tar heretofore referred to, or other heavy oil of low grade, that is poor in wax and high viscosity fractions, and when the fluxing operation has 110 been completed by the use of the steam jets for agitation, the fluxed product, constituting a low grade liquid fuel oil suitable for use as a bunker fuel, will be drawn out. The still will now be empty and ready for use 115 in its turn for conducting the final distillation operation and fluxing upon a fresh charge of bottoms from the continuous stills.

While I have in the foregoing described in considerable detail the preferred process in 120 accordance with my invention and have indicated some variants thereof, it will be understood that this is illustrative only and that my invention is not to be regarded as limited to the particular procedure described, except 125 in so far as such limitations may be included within the accompanying claims in which it is my intention to claim all novelty inherent in the invention as broadly as is permissible in view of the prior art. 130

What I claim is:

1. The method of distilling petroleum oils which consists in reducing the oil by continued distillation to a residuum of the consistency of a high melt-point pitch and mixing directly with the residuum while in heated, mobile state a heavy petroleum oil of low viscosity to produce a material capable of being handled as a fluid at atmospheric temperatures.
2. The method of distilling crude petroleum oil which consists in reducing the oil by continued distillation with open steam to a residuum of the consistency of a high melt-point pitch and mixing directly with the residuum while in heated, mobile state a heavy petroleum oil of low viscosity to produce a material capable of being handled as a fluid at ordinary atmospheric temperatures.
3. The improvement in the art of distilling crude oil which consists in continuing the distillation until the oil under treatment has been reduced to the consistency of a high melting point pitch, adding to said pitch a heavy petroleum oil of low viscosity and cold test and removing from the mixture and condensing the lighter vapors, a mixed fuel capable of being handled as a liquid at ordinary atmospheric temperatures being thereby produced.
4. The improvement in the art of distilling crude oil which consists in continuing the distillation until the oil under treatment is reduced to the consistency of a high melting point pitch, adding to said pitch heavy fluid residues from the cracking of petroleum oil, removing from the mixture and condensing the lighter vapors, a mixed fuel capable of being handled as a liquid at ordinary atmospheric temperatures being thereby produced.
5. The method of refining crude petroleum which consists in subjecting the oil to distillation until it has been reduced to the consistency of a high-melting-point pitch, treating the heavier portion of the distillate by a cracking operation yielding light oils and a heavy residue, and fluxing the said pitch by the addition thereto of the heavy residue of cracking.
6. The method of refining crude petroleum which consists in subjecting the oil to distillation until it has been reduced to the consistency of a high-melting-point pitch, separating the lubricating fractions and wax from the distillate, treating the separated heavy distillate by a cracking operation yielding light oils and a heavy residue, and fluxing the said pitch by the addition thereto of the heavy residue of cracking.
7. The method of refining crude petroleum which consists in subjecting the oil to continuous distillation with fire and steam until it has been reduced to the consistency of a high-melting-point pitch, treating the heavier portions of the distillate by a cracking operation yielding light oils and a heavy residue, and continuously fluxing the said pitch by the addition thereto of the heavy residue of cracking.
8. The method of refining crude petroleum which consists in subjecting the oil to continuous distillation with fire and steam until it has been reduced to the consistency of a high-melting-point pitch, separating the lubricating fractions and wax from the distillate, treating the separated heavy distillate by a cracking operation yielding light oils and a heavy residue, and continuously fluxing the said pitch by the addition thereto of the heavy residue of cracking.
9. The method of refining heavy asphaltic base crude petroleum, such as Mexican crude, which consists in subjecting it to continuous distillation with fire and steam until it has been reduced to a high-melting-point pitch representing approximately 25% of the mass of the crude, treating the heavier distillates by a pressure distillation cracking operation yielding light oils of the character of the gasoline and a heavy residue, and fluxing the said pitch by the addition thereto of the heavy residue of cracking.
10. A petroleum fuel product capable of being handled as a fluid and comprising a high-melting-point petroleum pitch fluxed with a heavy distillate substantially free of lubricating fractions and crystalline wax.
11. A petroleum fuel product capable of being handled as a fluid and comprising the bottom of Mexican crude petroleum reduced to about 25% by distillation with fire and steam, fluxed with a heavy distillate of the character of pressure tar.

EDGAR M. CLARK.
